UNITED STATES PATENT OFFICE

109,727

DESIGN FOR A LUGGAGE CARRIER FOR BICYCLES OR THE LIKE

Ewald F. Pawsat, Maysville, Ky., assignor to Wald Manufacturing Company, Incorporated, a corporation of Kentucky

Application January 28, 1938, Serial No. 74,688

Term of patent 14 years

To all whom it may concern:

Be it known that I, Ewald F. Pawsat, a citizen of the United States, residing at Maysville, in the county of Mason and State of Kentucky, have invented a new, original, and ornamental Design for a Luggage Carrier for Bicycles or the like, of which the following is a specification, reference being had to the accompanying drawing, forming a part thereof.

In the drawing:

Figure 1 is a perspective view of a luggage carrier for bicycles, showing my new design.

rier.

I claim:

The ornamental design for a luggage carrier for bicycles or the like, as shown.

EWALD F. PAWSAT.
